Letters Patent No. 2332, Dated June 10, 1866.

Design for a Trade Mark

The schedule referred to in these Letters Patent and making part of the same

To all whom it may concern

I, do, it is known, that I, Samuel E. Bassey, of New Haven, in the
county of New Haven, one state of Connecticut, have invented and designed
Trade Mark, And I do hereby declare the following, which taken in
connection with the accompanying drawings and the letter of
reference marked theron, to be a full, clear and exact description
of the same, and which said drawings constitute part of this
specification, and represent my design for a Trade Mark.

My invention relates to a design for a Trade Mark for the articles of
manufacture produced under the Patents granted in 1862, to C.
Crosby and Henry Hollings of New Haven, and to several other
men. Patents granted to C. C. Crosby for machines for making
Buffeting and Tape Trimming and for the articles produced
by said machines.

My design represents a female figure standing upon the rising
sun holding in the one hand a piece of Buffeting, in the other a
piece of Tape Trimming.

I claim the design for a Trade Mark as shown and described.
